UNITED STATES PATENT OFFICE

2,650,729

DUAL LOAD AND UNLOAD CHUTE DEVICE

Richard T. MacKay, Hollis, N. Y., assignor to The
Peelle Company, Brooklyn, N. Y., a corpora-
tion of New York

Application August 25, 1951, Serial No. 243,717

4 Claims. (Cl. 214—95)

1

Broadly speaking, the present invention relates to chute load and unload devices used particularly in conjunction with elevators which travel vertically within enclosed shafts. The devices are more specifically designed to be used in connection with dumbwaiter shafts in such buildings as hospitals where it is necessary to distribute medical supplies from a stock to various floors. In order to accomplish the distribution of medical or other supplies to the various floors, the dumbwaiter car is provided with a tilttable basket or tray which is normally adapted to be loaded with supplies at the stock room floor level. Elevator control buttons are provided at the stock room floor level whereby the movement of the elevator car is controlled. Also, the tilttable action of the tray is controlled from the stock room floor through electrical connections. In the use of the device, the tray is loaded with supplies at the stock room floor, after which the dispatcher pushes the respective button for the desired floor. When the car reaches the selected floor, the car is stopped by means of suitable limit switches. After the car is stopped, the unloading of the tray is accomplished through the means of electrical control buttons located at the loading floor. The unloading action of the tray causes the tray to be tilted to a position permitting the contents thereof to slide from the tray. The tray is preferably in the form of a chute and open at the end nearest the floor opening and with the farthest end thereof being closed.

The present invention does not involve the elevator car or the tilttable tray positioned therein, or the electrical control circuit thereof, but rather includes closures at each of the openings except the loading or stock room opening.

The principal object of the invention is the provision of closures which are adapted to effectively close off the floors from the elevator shaft from fire hazards and to provide extension chutes to carry supplies from and to the tilttable tray at each of the floors.

Another object is the provision of load and unload chutes rigidly positioned in and forming a part of each of the closures with hinged flaps or doors being located within the chutes and normally preventing the passage of drafts or flames therethrough.

A further object is the provision of means in connection with the hinged flaps or doors whereby the same are actuated by means of retarding cams located on and carried by the elevator car.

Other particular objects and advantages of the 55 and 5 are preferably formed of metal sheets hav-

2

invention will become apparent in the course of the following description, and that which is new will be pointed out in the appended claims.

The preferred and most satisfactory manner 5 of carrying out the principles of the invention is shown in the accompanying drawings, in which:

Figure 1 is a floor side elevation of one of the closures embodying the principles of the invention.

10 Figure 2 is a shaft side elevation of the device. Figure 3 is a vertical section taken through the device on line 3—3 of Figure 1.

Figure 4 is a detail vertical section taken 15 through the device on line 4—4 of Figure 2 and showing the flap-operating linkages, with the same being shown in the position assumed while the flaps are in closed position within the chutes.

Figure 5 is a detail section-elevation showing 20 the position assumed by the flap-operating linkage of the load chute while the flap is in open position and permitting loading of the car tray from the floor level.

Figure 6 is a detail section-elevation showing 25 the position assumed by the flap-operating linkage of the unload chute with the flap being in open position.

Figure 7 is a detail plan section, taken on line 30 1—7 of Figure 4, showing the load flap and its linkage, and with the flap being shown in closed position.

Figure 8 is a detail plan section, taken on line 35 8—8 of Figure 4, showing the unload flap and its linkage, and with the flap being shown in closed position.

Like characters of reference designate like 40 parts throughout the several views.

In order that the construction of the device 45 and the advantages thereof may be more fully understood and appreciated, I will now take up a detailed description thereof, in which the same will be more fully set forth.

Referring now to the drawings in detail, letter A designates the wall construction. Numerals 1 50 designate a closure frame member which is normally built in the wall construction and which provides a frame in which panels and chutes are positioned. 2 designates panels which are preferably of fire-resisting material and which are covered by a metal sheath, and with the same being secured in frame 1 by means of angle frame members 3.

Panels 2 and angle frame members 3 are so arranged to fit snugly around load chute 4 and unload chute 5. The load and unload chutes 4

ing sufficient rigidity to be self supporting when secured in place.

It will be noted, by referring to the various figures of the drawings, that load chute 4 slopes downwardly from the room side to the shaft side, and that unload chute 5 slopes upwardly from the room side to the shaft side. The shaft side of the load chute is positioned so as to be in register with the normal position of the tray carried by the elevator car. The shaft end of the unload chute is positioned so as to be in register with the tilted position of the tray carried by the elevator car.

Numeral 6 designates a pivoted or hinged flap member adapted to normally close the load chute against drafts and flame. Flap 6 is pivoted at the ends of its upper edge by means of shaft 7 at one end and at the opposite end by means of shaft 8. The flap is journaled on shaft 7 for free movement while shaft 8 is rigidly secured to the flap and with shaft 8 providing means through which the flap is actuated to open position.

The load flap 6 is operated from its normally closed position to its open position by means of a retiring cam member (shown in broken lines in Figures 4, 5 and 7) which is secured to and carried by the elevator car (not shown) through linkage 9, and with the retiring cam member being adapted to engage roller 10 of the linkage. One end of linkage 9 is journaled on shaft 11 which is provided with a suitable support 12 and which support is rigidly secured to the sides of chutes 4 and 5. The opposite end of linkage 9 is rigidly secured on shaft 8 which provides means for transferring the motion of the linkage to flap 6. A stop member 13 is secured on support 12 and provides means limiting the motion of linkage 9 in its normal position. It will also be noted, by referring to Figures 3, 4 and 5 that a recessed portion 14 is formed across the bottom of load chute 4 and provides a stop for the lower edge of flap 6. It will be noted that action of the cam member against roller 10 causes movement of the roller and the linkage away from the elevator car (not shown) and provides opening movement to flap 6 by means of shaft 8 being rigidly secured thereto. Flap 6 is adapted to close by gravity upon retraction of the cam member from its extended position.

Unload flap member 15 is pivotally supported on a pair of shafts 16, one of which is located at each end of the upper edge thereof. Flap 15 is operated from its normally closed position to its open position by means of shaft or pin 17 which forms a part of operating linkage 18. Pin 17 extends through arcuate slot 19 which is formed through the adjacent side of chute 5 with its end being secured into flap 15. Linkage 18 is pivotally secured at one end thereof on a shaft 16 and with the other end being journaled on shaft 21 which is secured into support 12. A cam-engaging roller 22 is interposed in linkage 18 and provides means actuating the linkage upon operation of the respective cam member. The cam member (shown in broken lines in Figures 4, 6 and 8) is a portion of a retiring cam mounted on and carried by the elevator car, and is adapted to engage roller 22 when in extended position and to operate linkage 18 and flap 15 from the positions shown in Figure 4 to the positions shown in Figure 6. Upon retirement of the cam member flap 15 returns to its normally closed position by gravity. A stop 23 is formed across the bottom of chute 5 and against which

the lower edge of flap 15 seats while in normally closed position.

In the operation of the device, the electrical system of the elevator is adapted to bring the elevator car to a stop at a selected floor and with the tray which is pivotally mounted in the car to be in register with a load chute 4. Should the tray contain articles to be unloaded, the tray is tilted by means of electrical control by the dispatcher to register with the unload chute at which time the respective retiring cam carried by the car is actuated and with the same operating the linkage 18 and swinging flap 15 to its open position whereupon the contents of the tray are dispensed through chute 5 onto a table or a suitable container (not shown) at that floor. After the contents have been thus unloaded from the tray, the cam member is retarded and the tray again assumes its normal position in register with the load chute 4, and with the unload flap returning to its normally closed position by means of gravity. Should it then be desired to load articles from the floor onto the elevator tray, the respective retiring cam is actuated by the dispatcher, and with the action of the cam member against roller 10 actuating the load flap to its open position and permitting articles to pass down chute 4 to the elevator tray, after which the cam is retarded and permitting load flap 6 to assume its closed position by means of gravity.

It will also be noted that a micro switch 24 is provided for interlocking the elevator circuit with load flap 6. The switch provides means breaking the elevator running circuit while the load flap 6 is in opened or partially opened position and prevents movement of the elevator car until the flap is again in its closed position.

It is desired that it be understood that, while the preferred manner of construction and operation has been shown and described, I am not to be limited to the exact construction and operation shown and described, but that minor changes may be made therein, insofar as the changes may fall within the scope of the appended claims.

What I claim is:

1. In a dual load and unload chute device, a pair of oppositely-sloping chutes positioned within a common frame with one end of each of said chutes extending into an adjacent elevator shaft and with the opposite ends of said chutes extending into a room area, a hinged flap fire stop located in each of the chutes, a linkage connected with and adapted to open each of the flaps, with each of the linkages being operable by means of a respective retiring cam located on and carried by an elevator car, and with each of the linkages being mounted on the frame adjacent its respective chute.

2. A dual load and unload chute device comprising a common frame member with a load chute and an unload chute positioned therein, with the inner end of each of the chutes extending into an elevator shaft and terminating adjacent to the vertical travel of an elevator car located within the shaft, with the outer end of the load chute being at a higher level than the inner end thereof and with the outer end of the unload chute being disposed at a lower level than the inner end thereof, a hinged flap fire stop member located within each of the chutes and adapted to close the same, means operating the hinged flap members from their closed positions to their open positions, and with the flap operat-

ing means being pivotally secured to the common frame with each being adjacent its respective hinged flap.

3. In a dual load and unload chute device, a load chute and an unload chute disposed in a frame, said load chute having its inner end in communicating relation with a vertically movable elevator car and with the opposite end thereof extending into a room area and located at a higher point than the inner end and providing means through which articles may be loaded onto the elevator car, a hinged flap positioned within the load chute, means swingably moving the hinged flap from its normally closed position to an open position, said unload chute having its inner end in communicating relation with the vertically movable elevator car and with the opposite end of the unload chute extending into a room area and located at a lower level than the inner end, a hinged flap member located within the chute and adapted to normally close the same, and means operating the flap member from its normally closed position to an open position.

4. In combination with an elevator shaft having a vertically moving elevator car therein, a closure comprising a common frame and forming a part of the elevator shaft walls, said closure having a load chute and an unload chute located therein, with the load chute sloping downwardly toward the elevator shaft and with the

15

20

30

unload chute sloping upwardly toward the elevator shaft, a hinged flap member forming a fire stop is located within each of said chutes, with each hinged flap member having a respective operating device connected therewith, with the operating devices providing means opening the respective flap members, and with each of the operating devices being pivotally secured to the common frame adjacent its respective hinged flap member.

RICHARD T. MacKAY.
